UNITED STATES PATENT OFFICE.

WILLIAM W. ROBERTSON AND WILLIAM E. McCLEARY, OF WORCESTER, MASSACHUSETTS, ASSIGNORS TO CROMPTON & KNOWLES LOOM WORKS, OF WORCESTER, MASSACHUSETTS, A CORPORATION OF MASSACHUSETTS.

TUBE FRAME FOR AXMINSTER LOOMS.

Application filed November 19, 1923. Serial No. 675,462.

To all whom it may concern:

Be it known that we, WILLIAM W. ROBERTSON, a citizen of the Dominion of Canada, and WILLIAM E. McCLEARY, a citizen 5 of the United States, both residing at Worcester, in the county of Worcester and State of Massachusetts, have invented a new and useful Tube Frame for Axminster Looms, of which the following is a specification.

This invention relates to tube frames for Axminster looms and more particularly to the construction of the brackets provided for the ends of the tube frames whereby

15 said brackets may be conveniently replaced.

In wide Axminster looms the weight of the tube frames and the spools which they carry is such that the frames are likely to fall out of the loom and either damage other 20 frames or be damaged themselves. The weight of the tube frames also causes increased wear on the chain engaging parts and this occasionally makes it necessary to replace the worn parts.

25 One object of our invention is to provide a bracket which is readily detachable from the tube frame by having associated therewith a block so positioned as to engage ears formed integrally with the tube frame.

30 A further object of our invention is to provide the bracket with inclined walls forming a tapered portion to be engaged by the integral ears and so disposed that the taper serves to prevent accidental dislodgment of the bracket.

35 A more particular object of the invention is to provide a bracket with a block and a chain engaging spring hook so arranged that the spring overlaps the block to prevent removal thereof from the bracket.

40 With these and other objects in view which will appear as the description proceeds, the invention resides in the combination and arrangement of parts hereinafter 45 described and set forth in the claims.

In the accompanying drawings, wherein one form of our invention is shown,

45 Fig. 1 is a front elevation of a portion of a tube frame having our invention applied thereto,

50 Fig. 2 is an end elevation of the structure shown in Fig. 1, and

Fig. 3 shows in perspective the component parts of our invention detached before assembling.

55

Referring more particularly to the drawings it will be seen that the tube frame 10 has soldered or otherwise secured thereto an angle plate 11 to which are soldered the yarn tubes 12. Each end of the spool 13 is 60 carried in a spool bearing member 14 the lower end of which is formed as shown in Figs. 2 and 3 with inclined faces 15 and shoulders 16. The lower end of the bearing member 14 is provided with a tapped 65 hole 17 for a purpose to be described.

The chain engaging arm 18 has a portion thereof extending parallel to the spool bearing member and is secured thereto in any manner as by rivets. The lower end of the 70 member 18 is of less width than the upper part as indicated at 20 and has shoulders 21 which are in horizontal alignment with shoulders 16 formed on the spool bearing. This reduced portion 20 is of less width than 75 that portion of the spool bearing lying between the inclined faces 15 and is provided with tapped holes 22 to receive screws 23 by means of which the chain engaging spring hook 24 may be held in place.

80 A block 25, shown in Fig. 3, has an upper portion 26 of substantially the same width as reduced portion 20 of the member 18, while the lower end of the block 25 is provided with extensions 27 so proportioned 85 as to give the lower end of the block substantially the same width as the widest portion of the spool bearing member 14.

The tube frame 10 is provided with a pair of ears 30 which extend from the vertical walls of the tube frame and have indent portions 31 which lie in a plane substantially perpendicular to the axis of the tube frame.

85 In assembling the tube frame the lower end of the spool bearing 14 is inserted between the ears 30, with the shoulders 16 resting on the ears 30, after which block 25 is secured to the spool bearing member 14 by means of screw 32 which passes through 100 the block and enters hole 17. The lugs 27 on the block define shoulders 28 which fit closely against the bottom of ears 30 and prevent upward movement of the bracket with

respect to the bar 10. The in-bent portions 31 of the ears 30 are spaced from the end 33 of the tube frame a distance not more than the thickness of the bearing member 14 so that the latter is held against motion longitudinally of the bar 10. The spring hook 24 is then screwed to the chain engaging member 18, the hook being so proportioned that the lower end thereof overlaps the block 10 and its screw 32 as shown at 34 in Fig. 2 to prevent accidental removal of the block and its screw. The ears 30 are then hammered until their inner faces lie against the inclines 15 formed on the spool bearing member.

While we have shown the inclined surfaces 15 yet we do not wish to be limited to this construction as the inclines may be omitted without loss of the shoulders 16, since the upper part of the spool bearing is wider than the lower part thereof.

When it is desired to remove the bracket from the tube frame the spring hook 24 is taken off, after which the block 25 may be removed. By means of a suitable tool the lower end of the spool bearing may then be driven upwardly to spread the ears 30 should the inclined surfaces be used.

From the foregoing description it will be seen that we have provided a bracket readily removable from the tube frame but held thereto so as to prevent transverse movement of the lower portion thereof with respect to the frame in either a vertical or horizontal direction; that a portion of the bracket is provided with inclined faces which assist in holding the bracket to the tube frame should the block and spring hook work loose; and that the spring hook is so disposed as to prevent accidental removal of the block.

Having thus described our invention it is apparent that changes and modifications

may be made therein by those skilled in the art and we do not wish to be limited to the structure set forth herein otherwise than as indicated by the appended claims.

What we claim is:

1. In a tube frame for Axminster looms, a hollow tubular member, ears integral therewith extending from opposite walls thereof and having portions bent toward each other and spaced from the adjacent end of the member, a spool bearing bracket located between the ears and between the bent portion of the ears and the adjacent end of the tube frame, shoulders formed on said bracket to engage the ears to limit motion of the bracket in one direction, and a removable block secured to the bracket and engaging the opposite ends of the ears to restrain motion of the bracket in the other direction. 50 55 60

2. In a tube frame for Axminster looms, a hollow tubular member, a supporting bracket therefor, ears formed in the tubular member embracing a portion of said bracket and engaging shoulders thereon and a removable block carried by the bracket and engaging said ears to restrain motion of the bracket transversely of the tube frame in one direction. 65 70

3. In a tube frame for Axminster looms, a hollow tubular member having ears integral therewith and a bracket embraced by said ears and having shoulders engaged by said ears to restrain motion of the bracket transverse of the tube frame in one direction, said bracket having inclined portions to engage said ears to resist motion of the bracket transverse of the tube frame in the opposite direction. 75 80

In testimony whereof we have hereunto affixed our signatures.

WILLIAM W. ROBERTSON.

WILLIAM E. McCLEARY.
